A. DELORME.
FRACTURE APPARATUS.
FILED MAY 16, 1921.

UNITED STATES PATENT OFFICE.

ALFRED DELORME, OF SPRINGFIELD, MASSACHUSETTS.

FRACTURE APPARATUS.

Application filed May 16, 1921. Serial No. 469,879.

To all whom it may concern:

Be it known that I, ALFRED DELORME, a subject of the King of Great Britain, but having declared my intentions of becoming 5 a citizen of the United States of America, residing at Springfield, in the county of Hampden and Commonwealth of Massachusetts, have invented certain new and useful Improvements in Fracture Apparatus, of 10 which the following is a specification.

This invention relates to improvements in surgical appliances, and more particularly to what is known as a fracture apparatus, which is designed to firmly hold the limb in 15 place while it is being dressed by the surgeon, and during the time of the healing of the wound.

An object of the invention is to provide 20 an apparatus that may be adapted to fit limbs of different lengths, and one that may be adjusted at different angles in order to make the patient as comfortable as possible.

A further object is to provide an apparatus that can be interchangeably used on 25 either the right or left limb.

A further object is to provide a device that will remain in a horizontal position; or, if desired, in a slightly inclined position.

Referring to the drawings: 30 Fig. 1 is a perspective view of the entire apparatus, showing in dotted lines a limb supported therein.

Fig. 2 is a detail view of the turn buckle for adjusting the angular relation of the 35 upper and lower portions of the apparatus.

Fig. 3 is a detail view of the removable ring member that is attached at the upper end of the apparatus, whereby the same may be used for either limb.

Fig. 4 is a detail view of the foot plate 40 adjusting device.

Fig. 5 is a detail sectional view on the line 5—5 of Fig. 1 of the joint between the upper and lower parts of the apparatus.

Referring to the drawings in detail: 1 and 2 designate parallel rods at the lower part of the apparatus. 3 and 4 are parallel rods at the upper end of the apparatus. These two sets of rods are pivotally connected together, as indicated at 5 and 6, and a detail of this joint is shown in Fig. 5 in which the interengaging portions are formed with inclined surfaces 7, having a space 8 therebetween. 9 indicates a brace rod for making the structure rigid at these pivotal points. This rod 9 is formed with a thread

10 at its ends to receive a thumb nut 11, whereby the joint may be firmly tightened. For the purpose of adjusting the angular relation between the upper and lower sets 60 of rods, brackets 12 are attached to the said rods in any suitable manner, as brazing, and attached to these brackets at the points 12 are the rods 13 and 14, which are threaded at their inner ends, as indicated at 15, see 65 Fig. 2. 16 indicates turnbuckles which, when rotated, on the rods 13 and 14, after the thumb nuts 11 are loosened, will change the angular relation of the upper and lower rods 1 and 2, 3 and 4. The thumb nuts 11 70 are then tightened. The brace 9, if desired, may be changed or moved into the dotted line position 9' for the purpose of comfort or convenience.

17 designates a ring having the arms 18 75 and 19 of different lengths attached thereto. These arms are recessed, as shown in Fig. 3 to receive the rods 3 and 4, and thumb nuts 20 are employed for clamping the ring to the rods. By reason of the difference in 80 length between the rods 18 and 19, the ring 17 may be reversed in order that the apparatus may be used on either the right or left limb of the patient.

For the purpose of accommodating the 85 apparatus to patients whose limbs are of different lengths, a bar 21 is slidably mounted on the rods 1 and 2. Spaced from, and connected to the bar 21 is a second bar 22, which is also slidable on the rods 1 and 90 2. 23 indicates thumb nuts for securing or clamping the bar 22 in different positions on the rods 1 and 2. 24 is an adjusting screw that is threaded through the bar 22 and engages the bar 21, whereby the latter bar 95 may be moved along the rods 1 and 2. 25 is a depending arm that is connected to the bar 22 and is formed with an opening at its lower end to receive the slidable rod 26, which rod is for the purpose of retaining 100 the apparatus in a substantially horizontal position, or in other words, to prevent it from tipping sidewise when in use. 27 is a foot plate which is pivotally attached to the bar 21 at 28. For the purpose of adjusting this plate, a thumb screw 29 is threaded through the depending bracket 30. The plate 27 is formed with a heel plate 31 for resting the limb in a comfortable position. 32 designates openings in the foot 110 plate 27 to receive strips of bandage, if desired.

It will be understood that the apparatus may be used by passing bandages around the rods 1 and 2, 3 and 4, as desired, for holding the limb of the patient firmly in place.

The position of the slidable rod 26 may, if desired, be so placed as to permit the frame as a whole to assume a slightly inclined position.

10 33 designates loops or rings that are pivotally connected to the bar 21 by means of the pins 34 to receive bandages, as desired.

15 17' designates leather or suitable covering for the ring 17, for the purpose of making it comfortable for the wearer.

What I claim is:

1. In an apparatus of the kind described, the combination with two sets of parallel bars which are pivotally connected together, 20 means including a turnbuckle construction that is directly attached thereto for adjusting the angular relation of the sets of bars and for fixedly retaining them in the adjusted position, and a removable ring member having rods fixedly attached thereto or detachably connecting the ring to the ends of one set of bars and to permit the ring member to be reversed, for the purpose described.

30 2. In an apparatus of the kind described, the combination with upper and lower sets of rods, means for pivotally connecting the rods together, means including rods connected thereto for adjusting the same, a 35 foot plate having slidable means mounted on the rods, means including a threaded rod carried by the slidable means and engaging the foot plate for adjusting its angular position, said means serving to retain the same 40 in its adjusted position, and means for retaining the apparatus as a whole in substantially a horizontal position when resting on a support as a mattress, for the purpose described.

45 3. In an apparatus of the kind described, the combination with a pair of rods, a foot plate, means for varying the position of the plate on the rods, and means including a horizontally slidable rod for retaining the 50 position of the apparatus substantially in

a horizontal position when resting on the bed, as described, said rod projecting on the opposite sides of the rods to give lateral support.

4. In a fracture apparatus, the combination with a pair of rods, a second pair of rods pivotally connected thereto, an arc-shaped brace bar connecting the rods at their pivotal points, and designed to be rotated about said points into a position either 55 above or below the rods, a turnbuckle construction connecting the pairs of rods and to the brace for varying the angular relation between the pairs of rods, a detachable ring member having arms of different 60 lengths for receiving the upper ends of one of the pairs of rods, whereby the ring member may be interchanged on the rods to permit the use of the apparatus on either the right or left limb, as described.

5. A fracture apparatus having in combination, two pairs of parallel members which are pivotally connected together, a single turnbuckle construction connected to each of the pairs of parallel members for varying the angular position of said members with relation to each other, a foot plate, a bar on which the plate is pivotally mounted, said bar being slidably mounted on one pair of the parallel members, a device for varying the angular position of the foot plate, means for longitudinally adjusting the foot plate on said members, and laterally slid- 75 able means for maintaining the apparatus in a horizontal position, as described.

6. In an apparatus of the kind described, two pairs of parallel members pivotally connected together, means including a slid- 80 able rod for engaging the upper surface of the mattress of the bed for maintaining the apparatus in a substantially horizontal position to prevent its turning or tipping over sidewise, as described, said rod projecting laterally beyond the pairs of parallel members, means for slidably supporting the rod including a depending member having an opening therethrough, the depending member being slidably mounted on one of the 85 pairs of parallel members.

ALFRED DELORME.
